US0D1095822S

(12) United States Design Patent (10) Patent No.: US D1,095,822 S
(45) Date of Patent:  Sep. 30, 2025

(54) PANTY WITH PAD

(71) Applicant: Tefron Ltd., Misgav (IL)

(72) Inventors: Laurie Christina Pollicino,
Massapequa, NY (US); Marianne
Villeneuve, Mirabel (CA)

() Term: 15 Years

(21) Appl. No.: 35/518,078

(22) Filed: Jul. 11, 2023

(80) Hague Agreement Data

Int. Filing Date: Jul. 11, 2023

Int. Reg. No.: DM/230668

Int. Reg. Date: Jul. 11, 2023

Int. Reg. Pub. Date: Aug. 18, 2023
